UNITED STATES PATENT OFFICE.

EDWARD C. SASSER, OF SPENCER, NORTH CAROLINA.

CINDER-DEFLECTOR.

1,130,110.

Specification of Letters Patent. Patented Mar. 2, 1915.

Application filed July 6, 1914. Serial No. 849,348.

To all whom it may concern:

Be it known that I, EDWARD C. SASSER, a citizen of the United States, and a resident of Spencer, county of Rowan, and State of North Carolina, have made and invented 5 certain new and useful Improvements in Cinder-Deflectors, of which the following is a specification.

My invention relates to a new and useful 10 improvement in cinder deflectors, and has for its object to provide a deflector that is formed from a single piece of sheet metal, and on which there will be but a minimum number of operations necessary to put the 15 same in its finished or completed condition.

Still another object of my invention is to 20 provide a cinder deflector so formed that when the cinders come in contact with the same they will either directly drop down- wardly below the window, or be deflected at such an angle that they will not be acted on by the suction formed by the moving train until below the level of the window.

Another object of my invention is to pro- 25 vide a cinder deflector that not only prevents the cinders from entering the windows at the sides, but also prevents them from entering from a position above the window, as it is well known that the cinders are shot up- 30 wardly from the engine and then fall, and at a declining angle are drawn in the open windows by the suction formed by the moving train.

Still another object of my invention is to 35 provide a cinder deflector, the sides and top of which present flat surfaces, with the ex- ception of the outer edges, which edges are so formed that the falling cinders will be cast or deflected outwardly so far that they 40 will have fallen below the lower levels of the windows before they are affected by the suc- tion formed by the moving train.

Still another object of my invention is to 45 provide a cinder deflector that will be easy to construct, cheap to manufacture, neat in appearance, and one that may be readily attached to or detached from the windowsill of the car.

With these and other objects in view my 50 invention consists of certain new and novel constructions and combinations of parts, as will be hereinafter more fully described and pointed out in the claim.

Referring now to the drawings Figure 1 55 is a perspective of the cinder deflectors attached to the side of a car. Fig. 2 is a view

in elevation and partly in section showing the deflector in place, and a resilient means between the side of the car and the said deflector. Fig. 3 is an enlarged horizontal fragmentary section taken on line 3-3 of Fig. 2 showing the resilient means between the side of the car, and also showing the angle of the deflecting rim. Fig. 4 is a detail perspective of a slightly modified 65 form, looking from the rear thereof.

In the drawings in Fig. 1, I have shown a fragmentary portion of a car 1 in which the window casings are of two sizes, that is the single and double casings generally alter- 70 nate, and it is therefore desirable for econ- 75 omy of metal etc., to construct the deflectors in two sizes, the one size for the single windows, and the large size for the double windows.

In forming my improved cinder deflectors a strip of sheet metal, generally of about six inches in width is bent substantially U-shape, thereby forming the sides 2 and 3 and the top or upper portion 4. The metal may be 80 of course of any desired strength and thick- 85 ness, and the length of the strip of metal is such that when bent to form, the side pieces will extend the full length of the stiles of the frame and at the top extends transversely 90 across the same, in the one case across the one window and in the other case across the two or double windows.

Near the outer edge 5 of the cinder de- 95 flector and extending from end to end of the same, that is including the top portion as well as the sides, the outer edge of the same is bent to form the deflecting flange 6, which flange is disposed at an obtuse angle to that of the sides and top and which angle 95 may be varied slightly from that shown in the drawings, if desirable, the idea being that if the cinders strike on the top portion lightly they will simply travel along the top portion and fall at the sides, or if they strike 100 with force enough to travel to the edge of the top portion they will be deflected out- wardly for as great a distance as possible and will then drop below the level of the bottom of the windows before acted upon 105 by the created suction.

It will be understood that most of the cinders will strike the upper portion 4 of the cinder deflector, but those that strike the side portions directly in their fall or from 110 being guided from the upward portion of the preceding deflector and will also either

drop downwardly and be guided by the flange or if striking with sufficient force will be deflected outwardly and at such a distance they also will have fallen below the 5 level of the windows before affected by the aforementioned created suction. The outer flange 6 may vary in width from a half an inch possibly to an inch and any cinders striking this flange will be deflected inwardly and also drop below the lower level 10 of the windows.

As shown in Figs. 1, 2 and 4 to form fastening means for the said deflectors, tongues or lugs 7 are formed at the rear of the said 15 deflectors, and although I have only shown three of these, as many may be provided as found necessary. These lugs or tongues 7 are then drilled or provided with the holes 8 through which may be passed the screws 9 20 which hold the deflectors to the side of the car. It will also be understood that any other similar form of securing means may be used without departing from the spirit of the invention. Also in Figs. 2 and 3 to prevent 25 any rattling of the deflectors, and to prevent marring the paint on the car, and as well as to form as perfect a joint as possible a resilient means 10 preferably of rubber is inserted between the car and the rear edge of 30 the deflector which rubber is provided with a groove 11, and into which the inner edge of the deflector is inserted and when the lugs 7 are drawn tightly against the car by the screws 9 the deflector and lugs will press the 35 rubber tightly against the outer surface of the car, forming a neat and tight joint between the said car and the deflector.

From the foregoing it will be seen that all the descending cinders will either travel 40 in the one instance along the top portion of the deflector and be guided by the outer deflecting flange 6 or if they strike with suffi-

cient force to overrun the same transversely they will be guided outwardly as far as possible and to such a distance that they will 45 have dropped to a position below the level of the window before being acted upon and drawn inwardly by the created suction of the car. Those that strike on the side portions will be either guided downwardly by 50 the flange or will be deflected outwardly and will also drop below the level of the windows as before mentioned. In Fig. 4 I have shown the lower edges of the side portions slightly rounded and of course either form 55 may be used, as described.

I am aware that cinder deflectors have been used with an upper portion extending across the top of the window as well as deflectors that have troughs or channel-shaped 60 sides, but so far as my knowledge extends I am not aware of any deflectors having the top and side portions provided with an outwardly extending flange so that the cinders will describe a ballistic curve of sufficient 65 magnitude to carry them below the sill of the window frame during their course of travel and while the car is in motion.

Having thus described my invention what I claim as new and desire to secure by Letters Patent is:—

A cinder deflector, comprising a body portion of substantially inverted U-shape and provided at its outer edge with a flange extending substantially throughout the length 75 of the said body portion, and said flange disposed at an obtuse angle to the plane of the said body portion.

Signed at Spencer and State of North Carolina, this 3rd day of July A. D. 1914. 80
EDWARD C. SASSER.
